ATTORNEYS

UNITED STATES PATENT OFFICE.

ISIDOR GREENWALD, OF NEW YORK, N. Y.

ESCAPEMENT FOR TIMEPIECES.

1,398,776.

Specification of Letters Patent. Patented Nov. 29, 1921.

Application filed April 4, 1921. Serial No. 458,232.

To all whom it may concern:

Be it known that I, ISIDOR GREENWALD, a citizen of the United States, and a resident of the city of New York, borough of Manhattan, in the county and State of New York, have invented a new and Improved Escapement for Timepieces, of which the following is a full, clear, and exact description.

- 10 This invention relates to time pieces and particularly to an improved escapement therefor and has for an object to provide a construction in which the usual hair spring is eliminated and a coil spring substituted.
- 15 Another object of the invention is to provide an escapement for time pieces in which a coil spring is utilized together with a system of gearing whereby the balance wheel may be caused to travel less or more than one 20 revolution upon each of its back and forth movements.

A still further object of the invention is to provide an escapement in which easily operated means for finally adjusting the parts is 25 presented.

In the accompanying drawing—

Figure 1 is a plan view with certain parts broken away illustrating the time piece and disclosing one embodiment of the escapement illustrating the invention.

Fig. 2 is an edge view of the structure shown in Fig. 1.

Fig. 3 is a detail fragmentary view illustrating the action of the escapement pawl 35 and escapement wheel.

Fig. 4 is a view similar to Fig. 3 but showing the parts in a different position.

Fig. 5 is a fragmentary sectional view through Fig. 1 approximately on line 5—5.

40 Referring to the accompanying drawing by numerals, 1 indicates a frame for containing various mechanism 2 of the time piece including the escapement mechanism 3. The construction of the clock mechanism 45 2 may be any suitable kind and varied as occasion may demand without departing from the spirit of the invention, as the invention refers particularly to the escapement mechanism.

50 From Fig. 1 particularly, it will be seen that the escapement mechanism includes a balance wheel 4, a supporting shaft 5 therefore, a pinion 6 rigidly secured to shaft 5 or formed integral therewith, a mutilated gear 55 7 meshing with the pinion 6, a coil spring 8 and regulating mechanism 9. The pinion 6

is continually in mesh with the tooth portion of gear 7 and said gear is rigidly secured to shaft 10 suitably journaled in the frame 1 and provided with an escapement 60 member or pawl 11 near the end opposite that carrying the gear 7. The pawl 11 is either formed integral with the shaft 10 or rigidly secured thereto and provided with a notch 12 having walls 13 and 14 adapted to 65 engage at different times the various teeth 15 of the escapement wheel 16 forming a part of the escapement mechanism. A short arm 17, preferably in the form of an eye is secured to the shaft 10 and extends therefrom so that one end of the spring 8 may be secured thereto while the opposite end is connected with a standard 18, which standard extends through an arc-shaped slot 19 in one of the plates of the frame 1. A regulating arm 20 is pivotally mounted at 21 on the frame 1 and is preferably rigidly connected with the reduced extension 22 of the standard or post 18 whereby when the regulating pointer 20 is shifted over the scale 23, the 70 75 tension of spring 8 will be varied. In order that the pointer 20 may be locked or held in any of its adjusted positions, a spring 24 is arranged between the clamping nut 25 and the pointer, said nut being tightened until 80 85 the spring gives sufficient friction to automatically lock the pointer 20 in any of its adjusted positions though permitting the operator to readily shift the same. It will, of course, be understood that the power of 90 spring 8 is very small.

It will be understood that the usual clock mechanism 2 is provided with a winding member, a main spring for rotating the gear 26 which meshes with a pinion 27, which pinion is connected with shaft 28 and said shaft is rigidly secured to a gear 29. The gear 29 meshes with a pinion 30 journaled in the frame 1 and carrying the escapement wheel 16 whereby said escapement wheel is 100 continually urged to rotate by the spring of the clock mechanism. The construction of the escapement wheel 16 is slightly different from ordinary escapements whereby the teeth 15 are preferably provided with comparatively straight radiating walls 31 on one side and an inclined preferably curved wall 32 on the opposite side whereby the wall or side 31 may properly engage the wall 14 of pawl 11 for actuating the same.

105 In operation, when the parts are standing still they usually assume the position

shown in Fig. 3 and when this position is assumed and the balance wheel 4 started to move manually, the pawl 11 will move as indicated by the arrow in Fig. 3 so that the periphery thereof will scrape by the outer end of the teeth 15^a until wall 13 has passed said outer end whereupon wall 14 will be opposite the wall 31 of tooth 15^a and said tooth will automatically move toward wall 14 but as the momentum of the balance wheel is considerable, wall 14 will strike wall 31 of tooth 15^a and move said tooth back a short distance, as for instance, to the position shown in Fig. 4. By this time the action of the balance wheel and spring 18 will have been overcome and the escapement wheel 16 will move under the action of the power transmitted thereto and will, in addition, move the pawl 11 quickly to substantially the position shown in Fig. 3 and in this movement will rotate the balance wheel 4 as well as bring the spring 8 under tension. As soon as the tension of spring 8 has overcome the momentum of the balance wheel 4 and begun to return the same, pawl 11 will begin again to move as indicated by the arrow in Fig. 3 and the action is repeated. By this construction and arrangement, the parts may be so proportioned, especially the pinion 6 and the mutilated gear 7 that balance wheel 4 may be given only a partial revolution upon each reciprocation or may be caused to revolve more than one revolution whereby the speed of the escapement may be varied. By the particular arrangement of the pointer 20, an easy adjustment of spring 8 may be had so that a proper back and forth movement of the balance wheel is secured according to the various conditions present in any particular size or constructed time piece.

What I claim is:—

1. An escapement of the character described comprising a balance wheel, a pinion connected with the balance wheel, a gear wheel meshing with said pinion, a coiled retractile spring connected with said gear wheel and positioned to normally hold said gear wheel in a given position, an escapement wheel and a pawl connected with said balance wheel, said pawl co-acting with the escapement wheel for transmitting power from the escapement wheel to the balance

wheel, said spring acting to return the balance wheel and pawl. 55

2. An escapement comprising a balance wheel, a shaft connected with said balance wheel provided with a pinion at one end, means associated with the opposite end for driving the balance wheel in one direction, a gear member meshing with said pinion for driving the balance wheel in the opposite direction and a spring acting on said gear member for causing the same to drive said balance wheel in said reverse direction. 60 65

3. In an escapement of the character described a spirally wound retractile spring and means for varying the tension thereof, said means comprising a post connected to one end of said spring, a swinging arm connected with said post and capable of moving the post when swung and means for locking said arm in any adjusted position. 70

4. In an escapement for time pieces a spring, a post connected with one end of said spring, a pivotally mounted arm connected with said post capable of shifting the post for varying the tension of the spring, a spring member co-acting with said post for locking the same in any adjusted position and means for maintaining said spring member under tension. 75 80

5. An escapement comprising a balance wheel, a shaft connected with said balance wheel provided with a pinion at one end, a gear member meshing with said pinion for driving the balance wheel in one direction, a gear wheel shaft secured to said gear member, means associated with said gear wheel shaft for driving said gear wheel in one direction, and a spring acting on said gear member for causing the same to drive said balance wheel in an opposite direction. 85 90

6. In an escapement of the character described a spring and means for varying the tension thereof, said means comprising a post connected to one end of said spring, an arm connected intermediate its length with said post, means at one end of said arm for pivotally mounting said arm so as to move said post in the arc of a circle, a spring member acting on said arm to frictionally hold the same in place, and locking means for compressing said spring member in any adjusted position. 95 100

ISIDOR GREENWALD.
